DESIGN FOR A CHILD'S BUBBLE PIPE OR THE LIKE

John E. Gilchrist, Chicago, Ill., assignor to Amatoy Corporation, Chicago, Ill., a corporation of Illinois

Application December 6, 1944, Serial No. 116,738

Term of patent 14 years

(Cl. D34—15)

To all whom it may concern:

Be it known that I, John E. Gilchrist, a citizen of the United States, residing at Chicago, in the county of Cook and State of Illinois, have invented a new, original, and ornamental Design for a Child's Bubble Pipe or the like, of which the following is a specification, reference being had to the accompanying drawing forming a part thereof.

In the drawing—

Fig. 1 is a perspective view of the child's bubble pipe or the like showing my new design, and

Fig. 2 is a side elevational view thereof.

I claim:

The ornamental design for a child's bubble pipe
or the like, as shown.

JOHN E. GILCHRIST.
